BUILDING CONSTRUCTION

Howard G. Smits, Pasadena, Calif.

Application February 10, 1939, Serial No. 255,644

9 Claims. (Cl. 108—4)

My invention relates to a building construction, and more particularly to a dome construction for use as an airplane hangar, or for exhibitions, or for any purpose for which it is desired that the 5 roof and walls be entirely supported from the peripheral foundation of the building, thus rendering unnecessary any pillars or columns within the structure. In plan, such structures may be circular or elliptical, or curved according to any 10 desired regular or irregular curve, or polygonal with its sides forming or approximating chords of such a curve, and it is to such structures that I refer herein as dome structures.

It is an object of my invention to provide a 15 dome structure in which the primary stress upon all of the structural members is axial whereby lighter and less expensive structural members may be employed than would be required if such members were subjected to bending moment.

20 It is another object of my invention to provide a structure and a method of assembling the same in which portions of the structure to be last erected may be readily employed as shoring or supporting members during the erection. More 25 particularly, it is an object of my invention to provide a construction and a method of erecting the same by which elements of the roof section or disc to be last installed are adapted for and used as shoring during the erection preliminary 30 to the installation of the roof section or disc.

In the use of such structures it is sometimes desired to have the top of the structure entirely 35 open to the atmosphere, and on other occasions it is desired to have it effectively closed against the elements. It is an object of my invention to provide such a structure having a roof section or disc capable of being easily and quickly installed in position in the structure and removed therefrom and which is stable against tendency to 40 deform or dimple under vertical load.

Likewise, in the use of such structures, it is 45 frequently desirable to have means for the entrance of light and/or air, and it is an object of my invention to provide a dome structure having such means in the form of bays offering the minimum impediment to the passage of light and air into and from the structure while contributing to its stability and rigidity.

Another object of my invention is to provide a 50 dome structure which includes a balcony supported entirely by such structure without the use of pillars or columns.

When such dome structures are employed as 55 airplane hangars, and for many other purposes, it is essential that one or more large door open-

ings should be provided without detracting from the stability of the structure. It is an object of this invention to provide such a construction having one or more door openings extending for a substantial part of its periphery and so constructed as to support the structure thereabove in the same manner as if the wall structure were continuous.

In the usual construction the girts or purlins or horizontal or circumferential members do not contribute to their full ability towards the stiffening and strengthening of the ribs or vertical or radial members against buckling because they are attached to only one side or flange of, and therefore are not in the principal plane of, the ribs 15 or vertical or radial members. It is an object of my invention to provide a construction having such members in the same plane whereby the walls and more particularly the ribs are greatly 20 stiffened and strengthened against buckling.

Still another object of my invention is to provide such a construction in which the girts or purlins or horizontal or circumferential members act not only as load supporting girders, but also as struts or staying members which may be called 25 brace members contributing to the rigidity of the construction.

The bracing ordinarily employed upon such structures to carry and distribute the wind and unequal vertical load thereon does not contribute 30 to the fullest possible extent to the stability of the main members or ribs. It is a purpose of my invention to so combine the structural members of the walls with the bracing receiving and distributing such loads thereon as to contribute by 35 such bracing to the rigidity of the main members or ribs and their resistance to buckling stresses. More specifically, it is an object of my invention to so arrange the structural elements and the 40 bracing of the walls that the intersection of the structural elements coincides with and is secured to intersections of the bracing members which are straight and continuous.

Still another object of my invention is the 45 provision of such a structure in which sections thereof may be prefabricated in the shop so that only their assembly is required in the field.

A further purpose of my invention is to provide a structure of the class described which is easy 50 to erect and as light and inexpensive as is consistent with the rigidity and stability of the structure.

Fig. 1 is a plan view of one embodiment of my 55 invention adapted for large structures, such, for

- example, as those having a span or diameter of more than 250 feet;
- Fig. 2 is an elevational view of the structure shown in Fig. 1.
- 5 Fig. 3 is an enlarged sectional view of such structure;
- Fig. 4 is a perspective view of one wall panel of this structure;
- Fig. 5 is a perspective view of a light bay panel;
- 10 Fig. 6 is a diagrammatic view of a portion of the roof taken as indicated by the line 6—6 of Fig. 1;
- Fig. 7 is a fragmentary sectional view taken as indicated by the line 7—7 of Fig. 2;
- 15 Figs. 8 to 11, inclusive, are diagrammatic views illustrating steps in the erection of the structure;
- Fig. 12 is a fragmentary sectional view of another embodiment of my invention better adapted for smaller structures, such, for example, as those having a span or diameter less than 250 feet;
- 20 Fig. 13 is a perspective view of a portion of wall of the embodiment illustrated in Fig. 12;
- Fig. 14 is a perspective view of another embodiment of my invention;
- 25 Fig. 15 is a diagrammatic view illustrating the method of erection of the construction shown in Fig. 14;
- Fig. 16 is a plan view of another embodiment of my invention;
- 30 Fig. 17 is an elevational view of the structure shown in Fig. 16;
- Fig. 18 is a sectional view of such structure;
- Fig. 19 is a perspective view of a portion of this structure in which the bracing characteristics are shown;
- 35 Fig. 20 is a plan view of an oval shaped structure having a modified form of roof section or disc;
- Fig. 21 is a diagrammatic sectional view of the construction shown in Fig. 20;
- 40 Fig. 22 is a fragmentary elevational view of a modified form of panel construction;
- Fig. 23 is a plan view of a structure of modified outline; and
- 45 Fig. 24 is a fragmentary sectional view taken as indicated by the line 24—24 of Fig. 3.
- Referring to the drawings, which are for illustrative purposes only, the numeral 21 of Fig. 3 indicates the foundation for the structure, which 50 is preferably of concrete. The foundation 21 may be continuous and polygonal in outline. Thus, if the building is to be circular in plan, the outline of the foundation represents a plurality of short chords connected together. Secured to the foundation 21, as by bolts 22, are bearing plates 23. At spaced points around the foundation 21, which may be the points of intersection of the sides of the foundation, ribs 24 are suitably secured to the bearing plates 23 as by angle plates, not 55 shown. As is illustrated in Fig. 3, the ribs 24 incline inwardly. The upper ends of adjacent ribs 24 are connected by a chord member or ring section 25. The ribs 24 and ring sections 25 may be advantageously formed of I-beams, and each 60 pair of adjacent ribs 24 with its connected ring sections 25 (or ring section 25 and lowermost girt) defines a section or arch panel 26 of the construction. As is illustrated in Fig. 4, each of the ribs 24 is common to two of the panels 26.
- 65 As illustrated in Figs. 1 and 2, the panels 26 are erected around the foundation 21, leaving only suitable door openings, and the chord members or ring sections 25 are connected together through the ribs 24 to provide a ring 27.
- 70 Rings, such as the ring 27, are described herein 75 as extending around the structure; by which I mean that they extend either completely around the structure or partially around it to permit of door and like openings therein.
- Included in each panel 26 are vertical bridge members 28, the horizontal distance between the upper ends of the ribs 24 being less than the horizontal distance between the lower ends. The bridge members 28 may be similarly disposed with their upper ends secured to the ring section 25 and their lower ends secured to a lowermost girt 30 connecting the adjacent ribs 24 near their lower ends. Stiffening members or purlins or brace members or girts 30 connect the adjacent ribs 24 intermediate their ends and are secured to the bridge members 28. The girts 30 and the bridge members 28 of each panel, which act as stiffening members and which may be formed of I-beams, are in the plane of the ribs and rings defining the panel; that is, the plane of the inner and outer faces of the girts 30 and the bridge members 28 coincide with or are within the planes of the inner and outer faces of the panel 26, as defined by the ring section 25 and the ribs 24.
- To aid in carrying the wind load and unequal vertical loads, and to stiffen the panels against buckling, each panel 26 is provided with a plurality of diagonal braces 31. As shown in Fig. 4, each diagonal brace 31 has one end secured to a rib 24 adjacent its connection to a girt 30 or ring section 25, and has its other end connected to the lowermost girt 30 or the ring section 25 adjacent its connection to a bridge member 28 or a rib 24. In this manner there may be an intersection of diagonals in each area defined by intersecting vertical and horizontal members. The spacing of the girts 30 is made such that the other intersections of diagonal braces 31 is superimposed upon the intersection of the girts 30 and the bridge members 28, and at such intersections the brace members are firmly secured to each other and to the adjacent intersection of girts 30 and the bridge member 28. The brace members 31 may also be rigidly secured together at their intersections in the trapezoids defined by the 30 vertical and horizontal members of the panel. By such construction the primary stress on the ribs 24, ring sections 25, girts 30, bridge members 28, and diagonal braces 31 is axially imposed, only the vertical live and dead loads and wind loads 35 subjecting the girts to bending stress, with the result that the additional strength which would be necessary if these elements were required to resist bending moment without the advantage of lateral support is not needed. Consequently, the 40 construction can be made of lesser weight and at lesser expense. It is to be noted that this is accomplished by the relative spacing of the girts and bridge members and that the diagonals are 45 straight and continuous through one panel, or if 50 desired, through two or more panels.
- Erected upon the lower row of panels 26, which is indicated by the numeral 32, is a second row 33 of panels 34. Rib members 35 of this second panel row 33 incline inwardly to a greater degree than 55 the ribs 24 of the lower panel row 32 and are suitably secured at their lower ends, as by welding or by riveted plates, to the upper ends of the ribs 24 of the lower row. It will be observed that the girts 30 and the ring section 25 of the panel 60 26 have the planes of their inner and outer faces coinciding with or within the planes of the corresponding faces of the ribs 24 and ring sections 25. Likewise, in each panel 34 of the second panel row 33, the girts and bridge members and 65

the ring section connecting the upper ends of adjacent ribs 35 have the planes of their inner and outer faces coinciding with or within the planes of the corresponding faces of the ribs 35. 5 It will be obvious that the ring sections connecting the upper ends of the ribs 35 will be of lesser length than the ring sections 25 therebeneath, and that the ring sections of the second panel row 33 are connected together through the ribs 35 to form 10 a ring 36. The panels 34 of the second row 33 include girts, bridge members, and diagonals assembled in the same manner as those described in connection with the panel 26.

In identically the same manner, third, fourth, 15 fifth, and sixth rows, 37 to 40, of panels may be erected, each with a ring at its upper periphery, as indicated by the numerals 37a to 40a of Figs. 1 and 2. Any of the rings above the lowermost ring 25 may act as compression or tension rings during 20 erection and after completion, depending upon the contour of the building and type of load thereon. While the third to sixth rows of panels 37 to 40 may be constructed in identically the same manner herein described for the first and 25 second rows, and include bridge members or studs or rafters, and girts or purlins and diagonals, I prefer to include in one or more of the rows of panels bays for the passage of light and air, which bays may extend continuously around the structure 30 in one or more rows of the panels, or may be disposed in any number of panels less than an entire row, that may be desired.

In the drawings, I have illustrated the bays as positioned in the third, fourth, and fifth rows of 35 panels 37 to 39 and as extending continuously around the structure except where the door trussing makes such bays inconvenient. In Fig. 5 there is indicated by the numeral 41 such a panel bay construction providing a bay opening 42. A 40 section 43 of the ring 36 is shown which, as before described, may be an I-beam. Connected to the ring section 43 and inclining and converging inwardly therefrom, are ribs 44 the upper ends of which are secured to a section 45 of the ring 37a. Each rib 44 in this construction is preferably a 45 channel. Secured to each of the ribs 44 adjacent the ring section 43, and extending vertically upwardly is a stud 46 which may be formed of two angles joined together with their connected 50 flanges projecting inwardly of the structure. The upper ends of the vertical studs 46 are attached to a section 47 of an auxiliary ring 48 which may be an I-beam. Connected to each end of the auxiliary ring section 47 and the adjoining end 55 of the adjoining ring section, is a joist or rafter 49, the other end of which is suitably secured to the inner end of the rib 44 therebeneath. Bridging 50 connects the ring sections 47 and 45 between the rafters 49 and is connected to purlins 51 which are attached to the rafters 49. Trussing 55 is provided between each rib 44 and its associated rafter 49 and stud 46 to form a truss member 111, the rafters 49 acting as roofing supports. This trussing includes braces 52 to 58, which may advantageously be formed of angles.

Two diagonal tie rods 59 are provided for increasing the rigidity of the bay panel construction. Each of the tie rods 59, which may be an angle, is connected at its outermost end to one of 70 the ribs 44 adjacent its outer end and is connected at its other end to the other rib 44 adjacent its inner end. A window beam 60 is connected to the ribs 44 near their forward ends and to the inner faces of the inner angle of each of the studs 75 46. The window beam 60 is adapted to support

any suitable closure, not shown, for the bay opening 42. It will be apparent that since the only bracing connecting the ribs 44 in their plane is the tie rods 59, there is substantially no obstacle presented to the free passage of light and air 5 through the bay 42 and between the ribs 44 to the interior of the structure. In a similar manner bay panels 61 and 62 may be provided in the fourth and fifth panel rows 38 and 39, respectively.

As illustrated in Fig. 3 there is secured to the 10 bottom of each of the channels forming the ribs of the fifth panel row a reinforcing member 63 cut upon a line in the plane of the lower surface of the rib 64 of the sixth panel row so that all but a portion of the lower flange adjacent the rib 15 64 is removed from the member 63, and a portion of the web of the member 63 is removed. In order to stiffen the web of the member 63 where the lower flange has been removed, an angle 63a 20 is secured to each side of the web adjacent its lower edge with the projecting flange of the angle lowermost. A connecting plate 63b is secured to the remaining portion of the lower flange of the member 63 and the lower flange of the rib 64 to stiffen their connection. A similar reinforcing 25 member 63c is secured to the bottom of each of the ribs 44 of the third panel row 37 and abuts against and is secured to the adjacent rib member 35 of the second panel row 33 so that its lower surface is in the plane of the rib 35. 30

Each of the ribs 64 of the uppermost panel row projects beyond the uppermost ring 40a and is provided with a connector plate 65 bolted thereto. The connector plates 65 are adapted to be bolted to a roof member or roof disc, indicated 35 by the numeral 66.

The roof disc 66 is formed of a plurality of identical trusses 67, a diagrammatic elevational view of one of which appears as Fig. 6. Referring to this figure, it will be seen that each of the roof 40 trusses 67 includes upper ribs 68 and lower ribs 69 diverging inwardly. These ribs may, with advantage, be formed of inwardly facing channels to which there is secured an inwardly directed angle. The ribs are trussed by four panels 70 to 45 73, there being included in the panel truss construction braces 74 to 85, illustrated in Fig. 6. When assembled in the roof disc, all of the roof trusses 67 are connected to a common king pin or pipe 86, and a supplementary rib 87 is attached 50 to the king pin 86 and the inner end of the lower rib 69.

As shown in Fig. 2, a part of the two lowermost panel rows 32 and 33 may be omitted to provide a door opening. Framing this door opening 55 is a lintel truss 88 supported at each end by vertical trusses 89. The lintel truss includes a pair of upper chords 90 and a pair of lower chords 91. As illustrated in Fig. 2, the trussing between each upper chord 90 and the lower chord 60 91 therebeneath may be formed in panels separated by vertical beams 92 with each panel including diagonal braces 93 connecting intersections of the vertical braces 92 and the chords at diagonally opposite corners of each panel. 65 The trussing between the upper chords 90 and between the lower chords 91 may likewise be formed in panels defined by transverse bracing 94 with diagonal braces 95 in each panel and, if desired, longitudinal and transverse braces 70 75 closing each panel and intersecting at the point of intersection of the diagonal braces. The truss 88 is stiffened by diagonals 110, one of which connects each upper chord 90 at one end of a panel to the opposite lower chord 91 at the other 75

end of that panel, one such diagonal being shown in Fig. 7.

The lower chords 91 project beyond the upper chords 90 a distance approximately equal to one of the panels, the extremities of the lower chords 91 being connected by end beams 96 which may be braced by diagonal members 97. The lintel 88 is supported by vertical trusses 89 attached to the lower chords 90 adjacent their ends.

- 10 Each of the vertical trusses 89 has inner and outer walls 98, triangular in outline, and a vertical end wall 99 defining the side of the door opening, and rectangular in outline, and an inclined opposite wall 100, also rectangular in outline. Each of these walls is suitably trussed with diagonal, horizontal, and vertical braces, not shown in detail.

As shown in Fig. 7, the ring 36 at each of the ribs 44 is connected by a suspender 101 to one of the horizontal braces 102 connecting the lower chords 91 of the door lintel 88, the points of connection of the suspenders 101 to the horizontal braces 102 being varied transversely of the lintel 88 along the lintel to permit the alignment 20 of the suspenders with the ribs 44 and the inclination of the suspenders on the same slope as that of the ribs 35, if they were employed.

As shown in Fig. 1, there is suspended from the second ring 36 a track 103 upon which doors, not shown, may roll between open and closed positions. The doors may be made to approximately conform in outline with the walls of the structure, their lower ends moving upon a track 104 provided in the foundation 21.

35 In erecting the structure described, the first two rows of panels 32 and 33 may be assembled in place, as shown, and supported during their erection by suitable guys anchored outside the foundation 21. In erecting the third and succeeding rows of panels, the roof trusses 67, with the auxiliary rib 87 and the king post 86 removed therefrom, can be employed as shoring. As indicated at 106 in Fig. 8, one of the roof trusses 67 placed on end provides a suitable support for the panels of the third row during their erection. After the third row of panels is installed, the fourth row may be held in position for installation by guys 107 extending from the horizontal members defining the bay opening 42 of the third panel row, or from the roof trusses 67, and thereafter, the roof trusses 67 remaining in shoring position, the fifth and sixth panel rows may be supported in position during erection by such guys 108. After the sixth panel 50 row is erected, the ring 40a in compression serves to maintain the structure rigid, it being a feature of this invention that the structure without the roof disc in place is stable and rigid.

The sixth panel row and the ring 40a being 60 in place, the roof trusses 67 are assembled to form the roof disc, indicated generally by the numeral 105, the structure being illustrated in dotted lines of Fig. 10. The roof disc 105 is elevated in any suitable manner, as by a block 65 and tackle secured to the uppermost ring 40a, into the position shown in full lines in Fig. 11, in which it is secured by bolting the connector plates 65 to the ribs 64 and to the upper and lower ribs 68 and 69 of such trusses. It will 70 be apparent that if it is desired, for any use to which the structure may be put, to have the structure open at the top, as illustrated diagrammatically in Fig. 10, the connector plates 65 may be easily disconnected from the ribs 68 and 75 69 and the roof disc 105, and the roof disc

lowered to the ground. The trusses 67 of the roof disc 105, or sections of the roof disc composed of a plurality of such trusses, may be secured together by bolts to facilitate their disassembly and removal from the structure after 5 the roof disc is disconnected from the structure.

Any suitable covering material, such as galvanized iron, or wood, for example, may be placed over the structure covering the panels in the first, second, and sixth rows and the roof disc 10 and the rafters, bridging and purlins 49 and 50 and 51 of the bay panels to enclose the structure.

From the foregoing description of the trussing and bracing or bridging, it will be apparent that it is so arranged that the primary stress on 15 all of the structural members, excepting the girts or purlins and the beam stresses in the ribs, is axial so that lighter and less expensive members can be employed than would be required if these members were subjected to primary bending moment. Inasmuch as the girts and purlins are in the same plane with the ribs or rafters instead of in a plane spaced from the plane of the ribs or rafters, the wall of the structure is greatly strengthened against buckling 20 and distorting stresses. Furthermore, because of the assembly of the diagonal bracing in a manner such that intersections of the ribs or rafters and the girts or purlins coincide with and are secured to intersections of the diagonals, the 25 bracing carries more effectively the wind load and unequal vertical loads which may be imposed upon the structure, and also contributes to the resistance of the ribs and walls to buckling 30 stresses. The girts and purlins in the structure 35 act not only as girders supporting load, but also as struts or staying members resisting deformation of the structure. Apparent, also, is the ease of erection contributed to by the use of the trusses of the roof disc as shoring members 40 during construction of the walls.

As may be seen by reference to Fig. 24 purlins, 180 in the uppermost panel row 40 may be connected to arch members or ribs 181 in a manner to provide additional rigidity to the structure. As 45 illustrated in this figure, each of the purlins 180 is cut parallel to its longitudinal axis near its lower flange so that a section 182 thereof may be bent downwardly. The lower end of the section 182 is cut at an angle on its lower surface 50 as indicated by the numeral 183, so that it is parallel to the upper surface of the lower flange of the arch member or rib 181. Thus the lower end of the section 182 may be welded to the upper surface of the flange of the rib 181. A reinforcing 55 plate 184 may be secured as by bolting to the web of the I-beam comprising the purlin 180 adjacent the juncture of the section 182 to the remainder of the purlin 180. The end of the purlin 180 may be secured to the rib 181 by angle 60 plates 185, one angle plate being bolted to each side of the web of the purlin 180, and to the web of the rib 181. A section is cut from the upper surface of each end of the purlin 180, as indicated by the numeral 186, to permit the reception of the 65 upper flange of the rib 181.

By dividing the web of the purlin in this manner and connecting the bottom flange of the purlin to or near to the bottom flange of the arch member or rib, and also connecting the purlin and rib 70 adjacent their top flanges, the lateral support given to the arch member or rib by the purlin is increased, with the result that a purlin of lesser depth can be employed, accomplishing a saving 75 in weight and expense. Further, this construc-

tion offers a means of fixing or firmly securing the ends of the purlins so that they are made stiffer and of greater resistance to deflection under load. This spreading of the flanges of the purlin 5 at the ribs increases the depth of the beam at the point of support and thus increases its resistance to bending moment.

In Figs. 12 and 13 is illustrated another embodiment of my invention. In this embodiment 10 the foundation 115, which may be of reinforced concrete, is formed in outline in a regular curve instead of upon chords or straight lines. Secured to the foundation 115 is a curved bearing plate 116 which may be a channel to which there is secured, 15 as by suitable angle plates 117, inwardly inclined ribs 118 connected at their upper ends by a ring section 119, the plane of which is normal to the axis of the ribs 118. As in the embodiment previously described, the ribs 118, which in this 20 instance may be inwardly faced channels, and the bearing plate 116, and ring section 119 which may be a flat bar, define a panel indicated by the numeral 120. This panel may include studs or bridge members 121 in the form of channels or 25 I-beams, and girts 122 of similar form, and diagonal brace members 123, or sheathing, all arranged so that the intersections of the girts 122 and bridge members 121 coincide with and are attached to intersections of the diagonal brace 30 members 123. In this embodiment each panel 120 may be constructed in the shop to be installed in the field, inasmuch as the panels 120 do not have common ribs 118 or ring sections 119.

Fig. 22 illustrates a modified panel construction 35 which includes ribs 118a, studs 121a, and ring section 119a, as previously described, but which includes only one-half the number of diagonals 123a used in the construction illustrated in Fig. 13. In the modified construction there are no 40 continuous girts, bridge members 122a being used to connect the intersection of diagonals and studs to only one of the adjacent studs 121a.

In the construction shown in Figs. 12 and 13, the ring sections 119 of the panels of each row are 45 secured to a bearing plate section or lower ring section 124 of the adjacent panel of the next upper row, preferably by bolts 125, so that the adjacent ring sections 119 and 124 form in the completed structure a ring 126 acting in the same 50 manner as the rings 25 and 36 to 40, inclusive, of the embodiment previously described. The vertical connection of adjacent ribs 118 of panels of each row, which is preferably by bolts, is staggered relative to the vertical connection of adjacent ribs of panels of adjoining rows a distance 55 of at least one-third of the width of the panel.

In the embodiment shown in Figs. 12 to 15, I have included only one row of bay panels, which is indicated generally by the numeral 127 and 60 which may be constructed in the same manner as the bay panels already described, so that the minimum impediment to the passage of light and air is offered by the diagonal brace members 128 connecting the ribs and ring sections of the bay 65 panel.

This structure includes a roof disc 129 which may comprise a king post 130 mounted upon a ring plate 131 secured by tie rods 132 to the innermost ring 133. Studs 134 are attached by connector plates 135 to the ring 133, and are attached at their inner ends to a tie plate 136 connected to the top of the king post 130. Suitable purlins 137 connect the studs 134. Here, also, the roof disc 129 may be quickly and easily removed from the wall structure by disconnecting 75

the connector plates 135, and the wall structure remains rigid and stable with the roof disc 129 removed.

As illustrated in Fig. 12, tie members 138, which may be I-beams, may be attached to one of the 5 rings 139 to extend inwardly therefrom, preferably in the plane of the ring 139 and substantially radial thereof. The lower ends of these tie members 138 are suitably attached to an inner ring 140 which may be formed of pipe. The inner ring 10 140 with the tie members 138 is adapted to support a balcony, not shown in detail, extending around part or all of the construction. If desired, the inner ring 140 or the balcony may be supported from or guyed to other rings in the 15 structure, though this is not essential. Such a balcony construction, so supported, may be employed in the embodiment of my invention illustrated in Figs. 1 to 11, inclusive.

In the erection of this construction, the first 20 row of panels is secured together upon the foundation 115 while supported by any suitable bracing. Thereafter, the second row of panels may be supported during construction in the manner shown by the dotted lines of Fig. 15, by a guy 142, 25 the lower end of which is anchored as by connection to the foundation 115 and which passes over a stiff leg 143 connected to the ring 126 with its upper end connected to the upper end of the 30 panels of the second row in a manner to support these panels until they are secured in place.

After the erection of the second panel row, which is indicated by the numeral 144, a similar guy 145, illustrated in dotted lines in Fig. 15, may be connected at its lower end to the first ring 35 126 and passed over a stiff leg 147 connected to and supported upon the ring 148 of the second panel row 144 and connected to the upper end of the panels of the third row to maintain the panels 40 in position during construction. In a similar 45 manner the panels of succeeding rows may be supported by guys extending over one or more stiff legs supported upon the rings of an adjacent or lower panel row during the process of construction. When the uppermost panel row and 45 ring 133 have been installed, the roof disc 129 can be elevated to its proper position as a unit and secured in place or assembled in its final position, as may be desired.

In Fig. 14 I have illustrated still another embodiment of my invention employing a foundation 150 regularly curved in outline and a curved bearing plate 151 to which inwardly inclined ribs 152 may be secured by connector plates 153 to define the sides of a panel 154. In this embodiment the 55 ribs 152 are attached through connector plates 155 to ring sections 156 which are formed of pipe. Girts, bridge members, and diagonals may be employed in these panels 154 in the same manner as previously described. Pipe forming the ring 60 sections 156 may be continuous around the structure to provide the rings 157, the connector plates 155 being secured thereto as by welding. This construction may be readily erected by supporting panels during construction with guys, as previously set forth. The provision of ring members in the form of pipe may, with advantage, be employed in that embodiment of my invention shown in Figs. 1 to 11, inclusive.

Fig. 16 illustrates a circular structure having a 70 foundation 190 of frusto-conical form projecting above the surface of the ground. In this construction, as illustrated diagrammatically in Fig. 18, a first panel 191 may be constructed in the manner previously described. A second panel 75

row 192, is illustrated in Fig. 19, includes a panel bay construction 193 similar to the panel bay construction 141 previously described, and thereabove an auxiliary panel row 194 of a construction similar to the panel 26 of Fig. 4. Ring sections 195 of the auxiliary panel row 194 are connected together to form a ring 196 the sections of which are subjected to axial loading. The ring 196 is supported by pillars 197 the lower ends of which are supported upon a foundation 198 within the structure. The pillars 197 are connected to each panel point, as illustrated in Fig. 19.

Above the panel row 192 are panel rows 199 to 202, inclusive, formed to provide light bays, as set forth in connection with the panel bay construction 41. Above the uppermost row of panel bays 202 is a panel row 203 similar to the panel row 40 of Fig. 1, to which is secured a roof disc 204 of construction similar to that hereinbefore described.

The foundations 193 and 198 may be connected by a concrete apron 205 to provide a support for seats surrounding the central arena enclosed by the structure.

In Figs. 20 and 21 there is illustrated an oval form of structure which includes a roof disc 167 having a central beam 168. A plurality of arches or ribs 169, illustrated as seven in number, are connected to each end of the central beam 168. In this construction a considerable part of the support of the roof disc is provided by the arches or ribs 169 at the ends of the structure, the upper ends of these arches or ribs intersecting because they are spaced around the portion of the structure having the smallest radius.

In Fig. 23 there is illustrated a structure of different outline involving two semi-circular ends 171 connected by an intermediate section 172 having straight sides. Arches or ribs 174 are provided in each semi-circular end and are of construction similar to that of the ribs previously described. Arches or ribs 175 are provided in the intermediate section 172. The arches 175 may be standard arches of no hinges, or standard two-hinge arches, or standard three-hinge arches. The ribs 174 are connected by ring sections 176 and the ribs 175 are connected by ring sections 177. The ring sections 176 are connected together through the ring sections 177 at the same elevation. In this construction the ring sections 176 function as the ring sections previously described. The ring sections 177, however, have no effect in reducing the moment in the arches or ribs 175 and are subjected only to tension and compression stresses, except in so far as they may act as purllins carrying vertical load upon the structure or staying members preventing buckling of the arches or ribs 175.

While the foregoing embodiments of my invention are capable of performing the objects and providing the advantages primarily stated, there are various other embodiments likewise capable of performing such objects and providing such advantages, and I therefore wish my invention to be understood as not restricted to the specific embodiments hereinbefore specifically described.

I claim as my invention:

1. In a dome structure, the combination of: arch panels extending from the base of the structure and including radially directed ribs and horizontal chord members intersecting therewith, said ribs and chord members being solid structural beams which bound said panels; means connecting said chords at each level whereby the stress upon said chord members is substantially

axial; and stiffening members within said panels so connected to said ribs and said chord members as to prevent their buckling in planes normal to the panels, the points of connection of the stiffening members with said ribs and chord members being intermediate the points at which the ribs and chord members intersect. 5

2. In a dome structure, the combination of: arch panels extending from the base of the structure and including and defined by radially directed ribs and horizontal chord members said ribs and members each being solid structural beams; means connecting said chords at each level whereby the stress upon said chord members is substantially axial; and stiffening members 15 so connected to said ribs and said chord members at points intermediate the panel corners as to prevent their buckling, said stiffening members being so connected to each other and said ribs and chord members as to be subjected to substantially no bending moment in response to load applied to the intersection of said ribs and said chord members at the corners of said panels. 20

3. In a dome-like structure, the combination of: rib members inclining inwardly of the base 25 of the structure; horizontal ring members intersecting said rib members to form wall panels for the structure bounded by said rib and ring members, said rib and ring members consisting of solid structural beams; a series of spaced stiffening members in each of at least some of said panels interconnecting adjacent ring members across the panels at points spaced from the panel corners to keep the ring members from buckling between panel corners; and a second series of 30 spaced stiffening members in each of the same panels interconnecting adjacent rib members across the panels at points spaced from the panel corners to keep the rib members from buckling between the panel corners, each of said series of 40 stiffening members in a panel being attached to the other series of stiffening members in the panel at the points of intersection of the stiffening members for mutual bracing of the stiffening members against buckling. 35

4. A dome-like structure as set forth in claim 3 in which the stiffening members of the first-mentioned series are substantially normal to the ring members that they interconnect, the stiffening members of the second-mentioned series are substantially normal to the rib members that they interconnect, and in which the stiffening members of both said series in a panel are within the bounding planes of the panel as defined by the opposite faces of said members that form the 50 panel. 55

5. In a dome-like structure, the combination of: rib members inclining inwardly of the base of the structure; horizontal ring members intersecting said rib members to form wall panels 60 for the structure bounded by said rib and ring members, said rib and ring members consisting of solid structural beams; a series of spaced upwardly extending braces reinforcing each of at least some of said panels internally and interconnecting adjacent ring members at points intermediate panel corners to prevent the ring members from buckling between panel corners; a series of spaced horizontal braces reinforcing each of the same panels internally and interconnecting adjacent rib members at points intermediate panel corners to prevent the rib members from buckling between panel corners; and intersecting diagonals reinforcing each of the same panels. 70 75

6. A dome-like structure as set forth in claim 5 in which said braces lie within the planes of the panels as defined by the opposite faces of said members that form the panels and in which the 5 upwardly extending braces and the horizontal braces are interconnected at their points of intersection for mutual stiffening.

7. In a dome-like structure, the combination of: rib members inclining inwardly of the base 10 of the structure; horizontal ring members intersecting said rib members to form wall panels for the structure bounded by said rib and ring members, said rib and ring members each consisting of solid structural beams; a series of spaced upwardly extending braces reinforcing each of at least some of said panels internally 15 and interconnecting adjacent ring members at points intermediate panel corners to prevent the ring members from buckling between panel corners; a series of spaced horizontal braces reinforcing each of the same panels internally and interconnecting adjacent rib members at points intermediate panel corners to prevent the rib members from buckling between panel corners; 20 a series of spaced diagonals inclined in one direction across each of the same panels; and a second series of spaced diagonals inclined in the opposite direction across each of the same panels, said braces and diagonals being interconnected at their points of intersection. 25

8. A dome-like structure as set forth in claim 7 in which said braces are within the planes of the panels as defined by the opposite faces of said members that form the panels and in which the 30 points of intersection of the diagonals coincide with points of intersection of the braces and at the coinciding intersection points two braces are interconnected with two diagonals, the braces and diagonal radiating in eight directions from the 35 coinciding intersection points.

9. In a dome-like structure, the combination of: rib members inclining inwardly of the base of the structure; horizontal ring members intersecting said rib members to form wall panels for the structure bounded by said rib and ring members, said rib and ring members each consisting of solid structural beams; a series of spaced stiffening members in each of said panels in some of said rows disposed normal to and interconnecting adjacent ring members across the panels at a plurality of spaced points along said ring members to keep the ring members from buckling between panel points; a second series of spaced stiffening members in each of the same panels disposed normal to and interconnecting adjacent rib members across the panels at a plurality of spaced points along said rib members to keep the rib members from buckling between the panel points, each 10 of said series of stiffening members in a panel being attached to the other series of stiffening members in the panel at the points of intersection of the stiffening members and being diagonally braced with said other series of stiffening members for mutual bracing of the stiffening members against buckling; auxiliary similarly 15 stiffened structural members forming a horizontal row of auxiliary panels extending outwardly from one of said ring members and diverging upwardly from a row of wall panels devoid of stiffening members and immediately 20 below said ring member to provide bays for the admission of light to the structure; upright structural members supporting said auxiliary 25 panels from a second and lower one of said ring members; and covering means extending over said auxiliary panels and the wall panels above 30 and below said auxiliary panels. 35

HOWARD G. SMITS. 40
